ARMORED SKIRT FOR TANKS

Juliana S. Dandini, Reno, Nev.

Application February 7, 1949, Serial No. 74,887

6 Claims. (Cl. 89—36)

1

The present invention relates to improvements in armored skirts for tanks, and its principal object is to provide a protective skirt for the undercarriage of a tank used in warfare.

From reports of tank casualties during the last war, it has been demonstrated that they are most vulnerable in the undercarriage, including the wheels, suspension means and tread of the caterpillar.

It is the object of the present invention to provide means for protecting these vulnerable parts by the employment of two rows of cylindrical bodies suspended about the undercarriage with limited freedom of swinging motion and arranged in such a manner that the bodies of the outer row cooperate in absorbing the impact of an anti-tank projectile in part, thus enabling a co-operating body of the inner row to arrest the projectile before it reaches the undercarriage.

It is further proposed to arrange the protective bodies in such a manner that they are free to swing and yield to irregularities in the ground surface so that they do not unduly hinder tank movements.

It is further contemplated to suspend the protecting bodies about the undercarriage in such a manner that they may be readily attached and detached for removal when the tank is not engaged in combat operations and for replacement of damaged ones.

Further objects and advantages of my invention will appear as the specification proceeds, and the novel features of the same will be fully defined in the claims attached hereto.

The preferred form of my invention is illustrated in the accompanying drawing, forming part of this application, in which:

Figure 1 shows a perspective view of a tank having my armored skirt attached thereto;

Figure 2 a vertical section, on an enlarged scale, through the armored skirt;

Figure 3, a top plan view of a portion of the armored skirt, and

Figure 4, a detail view, in side elevation, of a brush-clearing scythe attached to the front of the tank.

While I have shown only the preferred form of my invention, it should be understood that various changes or modifications may be made within the scope of the claims hereto attached.

2

without departing from the spirit of the invention.

Referring to the drawing in detail, the tank 1 may be of any suitable form well known in the art, and comprises an undercarriage 2 preferably of the caterpillar type and a body 3 supported thereon.

In carrying out my invention, I provide a steel girder or railing 4 on each side of the tank body 10 above the height of the undercarriage, the railings projecting outwardly beyond the undercarriage and running parallel to the tank body.

Portions of the railings may be made to extend about the front of the tank, or portions thereof, 15 as shown, leaving a front central portion free for accommodation of a scythe 5 adapted for cutting underbrush, dense vegetation, hedges or other obstacles.

The scythe 5 is preferably mounted for swinging movement into inactive position as shown in dotted lines in Figure 4.

The railing 4 has two rows of metallic cylindrical bodies 6 suspended therefrom, the two rows paralleling the tank body. The bodies are 25 sufficiently long to extend substantially to the ground surface, and are freely suspended so that they may yield when the bottom ends meet ground obstacles.

The two rows of cylindrical bodies run parallel to one another, one being fairly close to the tank 30 and being identified as the inner row, and the other being outside the inner row and being identified as the outer row. The bodies are suspended from the railing by means of the hooks 7 depending from the railing, and eyelets 8 on the cylindrical bodies engageable over the hooks. The railing has a downwardly projecting overhang 11 to protect the hooks and the eyelets.

The two rows of cylinders are preferably arranged in the manner shown in Figures 2 and 3, the two rows being located on opposite sides of a central plane, with the cylinders of each row slightly spaced from one another, and the cylinders of one row arranged in staggered relation with those of the other row. This gives each of the cylinders a limited freedom of swinging motion.

When the skirt formed by the two rows of cylindrical bodies is hit by an anti-tank projectile, identified by the numeral 9, the outer row

is intended to partly absorb the shock of the first impact by deflecting the projectile, while the inner row definitely arrests the flight of the projectile. This action takes place regardless of the angle at which the projectile strikes, and regardless of the location of the first point of impact.

A few possible hits have been indicated in the drawing in Figure 3. The upper projectile 9a is shown as striking one of the outer cylinders perpendicularly, but off-center, and it will be noted that the projectile is first deflected toward the neighboring cylinder, and then again toward the cylinder of the second row, so that when it reaches the latter cylinder its force has already been spent in part by the resistance offered by the cylinders of the first row.

It should be noted that due to the arrangement of the cylinders the resistance offered by the two cylinders of the first line is of progressively increasing strength. At first the projectile merely wedges itself between the two first cylinders struck. But each of the cylinders, in swinging sidewise through a limited distance, strikes adjacent cylinders, thereby increasing the resistance offered, and the adjacent cylinders again will spread the motion through further cylinders until the gap between the first two cylinders has increased sufficiently to allow the body of the projectile to pass.

The diameter and weight of the cylinders should be calculated according to the resistance desired for meeting anticipated impacts of projectiles and the spacing between the cylinders should be calculated to cause the projectile to spend a certain percentage of its force, say about fifty per cent, on breaking through the first line of the cylinders, so that the cylinder of the second line finally struck by the projectile will have to bear only a much reduced impact.

The percentage of resistance assigned to the cylinders of the first and second lines may, of course, be varied for best results as established by calculation, experimentation and experience in actual use.

A second projectile 9b is shown as making a direct hit centrally between two cylinders of the outer row, while a third projectile 9c strikes a glancing blow at one of the outer cylinders and in each case the result is approximately the same as previously described, the force of the impact spreading itself substantially as indicated by the arrows.

It will be noted that the cylinders are easily attached and detached, and may be readily removed for loading upon a special trailer drawn by the same tank, to be reapplied when combat is expected. Damaged cylinder may be readily replaced by new ones.

Each of the cylinders is preferably provided with an encircling band 10 of rubber or similar material to reduce rattling and excessive knocking while the tank is in motion.

The suspended bodies of the skirt have been described as being cylindrical, and this is the preferred form. But it should be understood that slight variations of the form are considered as falling within the scope of the present invention, as long as the effects produced are practically the same.

I claim:

1. An armored skirt for a tank of the character described, comprising a railing secured to the tank above the undercarriage thereof to project outwardly therefrom, a row of hooks secured upon the railing to project downward therefrom,

and a row of rigid, substantially cylindrical bodies having eyelets at their upper ends engaging over the hooks for swingably suspending the bodies from the hooks.

5. An armored skirt for a tank of the character described, comprising a railing secured to the tank above the undercarriage thereof to project outwardly therefrom, a row of hooks secured upon the railing to project downwardly therefrom, and a row of rigid, substantially cylindrical bodies having eyelets at their upper ends engaging over the hooks for swingably suspending the bodies from the hooks, the railing having a downwardly projecting overhang to protect the hooks and eyelets.

3. An armored skirt for a tank of the character described, comprising a railing secured to the tank above the undercarriage thereof to project outwardly therefrom, a row of hooks secured upon the railing to project downwardly therefrom, a second row of hooks secured upon the railing to project downwardly therefrom in parallel relation to the first row and in staggered relation with respect to the hooks of the first row, and two rows of rigid, substantially cylindrical bodies having eyelets at the upper ends engaging over the hooks for swingably suspending the bodies from the hooks.

4. An armored skirt for a tank of the character described, comprising a railing secured to the tank above the undercarriage thereof to project outwardly therefrom, a row of hooks secured upon the railing to project downwardly therefrom, a second row of hooks secured upon the railing to project downwardly therefrom in parallel relation to the first row and in staggered relation with respect to the hooks of the first row, and two rows of rigid, substantially cylindrical bodies having eyelets at the upper ends engaging over the hooks for swingably suspending the bodies from the hooks, the railing having a downwardly projecting overhang to protect the hooks and the eyelets.

5. An armored skirt for a tank of the character described, comprising a railing secured to the tank above the undercarriage thereof to project outwardly therefrom, a row of hooks secured upon the railing to project downwardly therefrom, a second row of hooks secured upon the railing to project downwardly therefrom in parallel relation to the first row and in staggered relation with respect to the hooks of the first row, and two rows of rigid, substantially cylindrical bodies having eyelets at the upper ends engaging over the hooks for swingably suspending the bodies from the hooks, all the bodies being spaced from one another for limited freedom of swinging movement, and the spacing being relatively minor as compared with the diameter of the bodies so as to cause the latter to form a solid barrier to any missile arriving from any direction.

6. An armored skirt for a tank of the character described, comprising a railing secured to the tank above the undercarriage thereof to project outwardly therefrom, a row of hooks secured upon the railing to project downwardly therefrom, a second row of hooks secured upon the railing to project downwardly therefrom in parallel relation to the first row and in staggered relation with respect to the hooks of the first row, and two rows of rigid, substantially cylindrical bodies having eyelets at the upper ends engaging over the hooks for swingably suspending the bodies from the hooks, all the

bodies being spaced from one another for limited freedom of swinging movement, and the spacing being relatively minor as compared with the diameters of the bodies so as to cause the latter to form a solid barrier to any missile arriving from any direction and the railing having a downwardly projecting overhang to protect the hooks and the eyelets.
